William Clinton

Attorney

UNITED STATES PATENT OFFICE.

PIERRE JOSEPH HENRI BERNARD, OF MONTREAL, QUEBEC, CANADA.

AIR HEATER.

Application filed August 24, 1922. Serial No. 584,064.

To all whom it may concern:

Be it known that I, PIERRE JOSEPH HENRI BERNARD, a subject of the King of Great Britain, residing at Montreal, Province of Quebec, Canada, have invented certain new and useful Improvements in Air Heaters; and I do hereby declare that the following is a full, clear, and exact description of the invention, such as will enable others skilled in the art to which it appertains to make and use the same.

The present invention relates to new and useful improvements in an air heater and has for one of its objects the provision of a device which may be heated by gas, oil, or electricity; it is an improvement over my former Canadian Patent No. 216,324.

Among the principal objects of the invention is the provision of a radiator, of the type referred to in which the use of only a comparatively small amount of water is necessary. In connection with such a radiator the invention contemplates the use of a specially designed head by means of which an efficient circulation of water throughout the radiator is established, such head being simple in its structure and operation.

Another object of this invention is to provide a device of the character described, by which the heating element is completely enclosed permitting the circulation of air only from the bottom to the top, no air being admitted in contact with the heating surface by the sides; thus, the cooler air being generally on the floor is admitted by the bottom and heated through the device, and finally exhausted through its upper part, thus insuring an even temperature all over the room.

A further object of this invention is to obtain a device of the character described, provided with appropriate means for preventing the water reservoir from being heated by the heat generated by the apparatus, thus preventing the evaporation of the water contained therein.

Other objects and advantages of the invention will be apparent as the description continues, while others will be definitely pointed out.

The invention is fully disclosed in the following description and in the accompanying drawings in which:

Figure 1 is a rear perspective view of the device, showing the rear wall open to disclose the interior;

Figure 2 is a front elevation;

Figure 3 is a side elevation of the interior of the device heated by gas, the casting being in section, this view corresponding to Figure 1;

60

Figure 4 is a similar view of the device heated by electricity;

Figure 5 is a section through the header at a corner of the radiator; and

Figure 6 is a fragmentary perspective detail view of the header.

Referring to the various views by corresponding reference characters throughout, and particularly to Figure 1, the frame or body of the device consists of a box like member 1 mounted on a set of legs 2. A perforated cover 3 is superposed on the body and is designed in any desired manner to render the device of attractive appearance. At the end a closure 4 is hinged for obtaining access to the burner and heater.

A plurality of props 5 are mounted on the base of the body and serve to support a radiator 6. As will be seen from Figure 1, this radiator comprises a plurality of box like structures 7, preferably rectangular, supported in parallelism and spaced from one another on the props 5. Communication is established among these various sections or chambers by means of headers 10 fixed at the corners thereof. Each header includes a substantially U-shaped member 11 (Figure 5), closed at its open side by a cap 12, thus forming a sleeve like structure which is substantially square or rectangular in cross section. In one edge of this device is formed a plurality of notches 13 in which the corners of the sections 7 are received. The corners of the sections 7 are cut away, as at 14 (Figure 5) in order to establish communication with the headers, the edges of the cut away portions being soldered or otherwise connected to the headers to insure against leakage.

At the lower corner of the frame (Figure 1) is supported an oil burner 16 which is regulable by means of the screw 17. This burner is supplied from a reservoir 18 mounted at one end of the device and provided with the usual tank 19. A supply pipe 20 leads from the tank 19 to the burner and is provided with a cut-off valve 21.

Above the burner is supported a hood or covering member 22 in which is supported a circulation water heater 22' shown in Figure 3. This heater comprises a dome 22', which is sustained within the hood 22 by

means of the water outlet pipe 24 passing through the upper portions of both members.

The lower header 32 of the radiator is placed in communication with the water heater by means of a pipe 33 extending into the heater 22'. The water upon being heated circulates through the heater and finally ascends through the pipe 24, from which a pipe 34 leads to one of the upper headers 35 of the radiator.

At the top of the frame and above the pipe 34 is supported a water reservoir or supply tank 36. The upper header 37 of the radiator, which is opposite the header 35 communicates with the reservoir by means of a return pipe 38. A condenser 39 is interposed between this return pipe and the reservoir. A water supply pipe 40 connects the lower portion of the reservoir with the heater 22' through a connection 41. The lower end of the supply pipe is fitted with a cock 42 for draining the system. The course of circulation is as follows: The water first enters the heater through the supply pipe 40, and is then caused to rise through the pipe 34 into the upper portion of the radiator. Because of the large exposed surface of this radiator, the heat of the water is dissipated into the surrounding atmosphere as the result of which the water cools and condenses, as shown by the arrows in Figure 3. Finally it reaches the lower header 32 and thence returns to the water heater through the short pipe 33. Any steam that may be formed in the radiator because of excessive heating or other reasons rises through the pipe 38 and passes to the condenser 39, being returned from the latter to the reservoir for further circulation through the system.

A heater adapted for use with an electric element is shown in Figure 4. In this instance, the hood 22 at a point 43 is provided with a bracket 44, for supporting an electric element 45. The electrical connec-

tions 46 to the heating element are of the usual type which may be regulated to three intensities of heat by means of the switch 47. 50

The reservoir 36 supplying water to the heater can be filled from its upper portion through an opening 67 normally closed by a cover 68, thus preventing the unnecessary evaporation of the liquid. I have found, 55 through actual experiments, that with such a construction water should be added to that in the reservoir only twice a year.

In view of insuring the safety of the device, when heated by means of oil, the oil reservoir 18 is located exteriorly of the opposite side of the burner, this reservoir is also provided with a glass gauge 69, so at any time the amount of oil in said reservoir can be easily seen. It should be also noted that in order to help the combustion of the oil or gas and secure the proper draft, the side of the radiator adjacent the burner is provided at its lower portion with apertures 17' which may be closed or opened 65 at will by means of a conventional shutter (not shown).

While specific embodiments of the invention have been illustrated and described, it is to be understood that various alterations 75 in the details of construction may be made without departing from the spirit of the invention as indicated by the appended claim.

Having thus fully described the invention, what I claim as new and desire to protect by Letters Patent is:—

A radiator including a plurality of hollow rectangular sections arranged in spaced relation, headers arranged at the vertices 85 of said sections for placing the sections in communication with the headers, said headers being notched for the reception of the sections, said sections being cut away at the portions received within said headers. 90

In witness whereof I have hereunto set my hand.

PIERRE JOSEPH HENRI BERNARD.
